Primary Examiner—Jane E. Corrigan

[57] CLAIM

The ornamental design for the invalid seat cushion, as shown and described.

DESCRIPTION

FIG. 1 is a front, top and right side perspective view of an invalid seat cushion showing my new design;

FIG. 2 is a top plan view, the bottom being substantially identical;

FIG. 3 is a view like FIG. 1 with the insert removed; FIG. 4 is a front elevational view with the insert in place;

FIG. 5 is a view like FIG. 3 of a modified form of an invalid seat cushion showing my new design wherein the insert is C-shaped; and

FIG. 6 is a top plan view thereof with the insert in place, the bottom being substantially identical.

FIG. 1

FIG. 2

FIG. 4

FIG. 6
